UNITED STATES PATENT OFFICE.

PETER A. MAC EACHERN AND NOLEN O'DANIEL, OF DOUGLAS, ARIZONA.

ORE-GRINDING MILL.

1,233,086.

Specification of Letters Patent. Patented July 10, 1917.

Application filed August 12, 1916. Serial No. 114,634.

To all whom it may concern:

Be it known that we, PETER A. MAC EACHERN and NOLEN O'DANIEL, citizens of the United States, and residents of Douglas, in the county of Cochise and State of Arizona, have invented a certain new and useful Improvement in Ore-Grinding Mills, of which the following is a specification.

Our invention is an improvement in ore grinding mills, and has for its object to provide a mill of the character specified wherein a fixed and a rotatable member are provided, the said fixed member being circular and arranged coaxially, and the rotatable member being mounted to rotate with respect to the fixed member, the said members having registering circular runways or rotaries in which are mounted series of balls; and wherein a launder encircles the sections, being secured to the fixed member for receiving the ground material, and wherein the members, the launder, and the runways are sectional and detachably connected to permit detachment and replacement of any portion thereof.

In the drawings:

Figure 1 is a side view of the improved mill;

Fig. 2 is a transverse vertical section;

Fig. 3 is a top plan view with parts broken away; and

Fig. 4 is an enlarged section through the rotaries and grinding balls.

The present embodiment of the invention comprises a base and a top or cover of similar construction, the top or cover being arranged to rotate with respect to the base to grind the ore. The base is sectional, consisting of four similar sections which are secured together to form a circular structure having a central hub.

Each of the sections 1 has radial ribs 2 and 2^a, the ribs 2 being at the straight sides of the sections, while the ribs 2^a are intermediate the said sides. The ribs 2 of the sections abut and are secured together by bolts and nuts 3 to hold the sections into the circular structure, and all of the ribs 2 and 2^a are supporting ribs for the base. It will be noticed from an inspection of Fig. 2, that the structure as a whole has a slightly conical top being highest at the hub 4 and gradually inclined outwardly toward the periphery. The top or cover is also composed of sections 5 of quadrantal form having radial ribs 6 at their straight

sides, and ribs 6^a intermediate the ribs 6. The ribs 6 abut and are secured together by bolts and nuts 7 to form a complete structure. The top or cover has a central hub 8 which is coaxial with the hub 4. When the base and cover are in proper position, the ribs 6 and 6^a do not extend to the hub as do the ribs 2 and 2^a of the base, being approximately halfway from the periphery to the hub. An upstanding circular flange 9 is provided integrally with the sections, and also sectional, the said flange forming a pulley for engagement by the belt 10 to rotate the top or cover with respect to the base. This flange is braced externally by the ribs 6 and 6^a and internally by bracing ribs 11 which are of approximately the same depth at the flange as the flange, but decrease in depth toward the hub, and bolts and nuts 13 are provided for connecting the abutting ribs 11.

The adjacent faces of the top or cover and base have arc-shaped ribs 14, which are so arranged with respect to the sections that so when the sections are bolted together, the ribs will form continuous circular ribs parallel with each other and with the ribs of the top or cover registering with the ribs of the base.

Tracks or runways 15 are supported by the ribs of the top or cover and the base, each of said tracks or runways being provided at its opposite side edges with outwardly extending flanges 16 which rest upon the ribs 14, while the bodies of the tracks or runways rest upon the body of the base, and the said bodies at the cover are connected with the cover in the manner seen in Fig. 4. Bolts 17 are passed through the bodies of the tracks or runways of the top or cover, and through registering openings in the top or cover, and are engaged by nuts above the top or cover to hold the runways in place.

It will be noticed from an inspection of Fig. 4 that the openings for the bolts in the runways are reamed or counterbored, to receive the heads of the bolts, and these bolts are arranged between the ribs 6 and 6^a in lines radial with respect to the top or cover. The runways of the top or cover register with the runways of the base, and within each of said runways is arranged series of hardened steel balls 18, the said balls fitting the runways; that is, the curve of the runways corresponds to the curve of the periphery of the balls. The balls of each run-

way are in contact and in the present instance five series are provided.

The ore being ground, is fed into the hub 8 of the top or cover, by means of a feeding launder 19, and a cover or stop plate 20 covers the upper end of the hub 4, being secured to the said hub by screws, as shown. The balls 18 space the top or cover above the base and the hubs 4 and 8 are similarly spaced so that the material fed through the launder 19 will be deflected by the plate into the runways or rotaries. This material will be ground between the balls and the runways and will work its way out toward the periphery of the mill.

In practice there will be a fall of a quarter of an inch to the foot from the center or intake to the circumference. The launder encircles the mill for receiving the ground material and the said launder is composed of sections 21 which have depending ribs 22 at their ends, the ribs abutting and being secured together in a water-tight manner. The inner walls of the sections are bolted to the peripheral rib 11 of the base, as indicated at 23, and the launder has a discharge or outlet 24. The outer face of the peripheral rib 11 of the base is rabbeted to receive the inner wall of a trough, and the material ground discharged directly into the launder.

The steel balls and the rotaries which are also of hardened steel, form the grinding faces of the machine, and since each rotary or circular runway is sectional, and since any section may be detached, the parts may be readily replaced or renewed, should they become worn or broken.

In operation the ore which is reduced to the proper size, depending upon the size of the mill, is fed into the hub 8. As the top rotates, the material will pass out toward the periphery, and will be finely ground between the balls of the runways, finally reaching the launder at the proper mesh.

We claim:

In a mill of the character specified comprising complementary members, each having radial ribs on its outer face and parallel circular ribs on its inner face, the circular ribs of the two members coinciding, half-round runways placed between the circular ribs of the members and touching the members on medial lines and having outer flanges at their edges to overlap and bear against the ribs, and balls arranged in the runways.

PETER A. MACEACHERN.
NOLEN O'DANIELL.
